UNITED STATES PATENT OFFICE.

JOHN E. TOOHEY, OF GRAND RAPIDS, MICHIGAN.

FRAMING-MACHINE.

1,254,177.

Specification of Letters Patent. Patented Jan. 22, 1918.

Application filed February 5, 1916. Serial No. 76,381.

To all whom it may concern:

Be it known that I, JOHN E. TOOHEY, a citizen of the United States of America, residing at Grand Rapids, in the county of Kent and State of Michigan, have invented certain new and useful Improvements in Framing-Machines; and I do hereby declare the following to be a full, clear, and exact description of the invention, such as will enable others skilled in the art to which it appertains to make and use the same.

This invention relates to a framing machine of especial value and utility in framing timbers such as are used in building trestle work and the like for railroad bridges. It is the object and purpose of my invention to provide a device of this character which will consist of an attachment that may be readily secured to or removed from the ordinary hand car which section gangs on railroads use, and the device may be operated by a gasolene engine which furnishes the motive power for the hand car. A further object of the invention consists in the provision of an attachment of this kind which may be very cheaply and easily manufactured consisting of few parts but of durable nature so as to withstand the more or less rough usage to which it may be subjected. To these ends I have constructed a device, the structure and operation of which is illustrated in the accompanying drawings, in which:

Figure 1 is an elevation showing my attachment applied to a hand car and the method of its use.

Fig. 2 is a sectional view taken on the line 2-2 of Fig. 1 and looking in the direction indicated by the arrows.

Fig. 3 is a view on a larger scale showing the opposite side of the attachment from that shown in Fig. 1; and

Fig. 4 is a plan view of said attachment.

Like reference characters refer to like parts throughout the several views of the drawings.

My invention is adapted to be applied to a hand car, the platform of which is indicated at 1, it being movably supported by the usual wheels 20 so that it may be moved over railroad tracks. An internal combustion engine indicated at 3 is located above the platform and may be of any conventional construction including a shaft 3^a on which the fly wheels 4 are mounted. A drive wheel 5 is also secured to the shaft 3^a adjacent one of the fly wheels and by means of

a belt interposed between this wheel and a shaft on which the wheels 2 are mounted; it will be evident that the engine may propel the hand car over the suitable tracks. In practice the engine is secured to a base timber 6 which lies lengthwise and centrally of the platform of the car.

The attachment which I use in connection with the hand car for framing timbers includes a support 7 made preferably from cast iron, its upper end being formed with a bearing 8 to receive a pin 9. A pair of spaced apart bars 10 are used which are pivotally mounted upon the pin 9, one at either side of the bearing 8, it being evident that these bars may be detached at any time by withdrawing one of the cotter pins 11 so that the pin 9 may be readily removed. Bars 10 extend forwardly a distance beyond the end of the platform 1 and at their outer ends are connected by a block 12 also preferably formed of cast iron though the material used may be varied. Between the ends of the bars 10 another block 13 is secured serving to brace and strengthen the structure as a whole and also serving an additional function which will later be described.

The block 12 is bored to form a bearing for the cross shaft 14 one end of which may have attached thereto any suitable rotary cutter such as indicated at 15 while the opposite end carries a small drive pulley 16, an endless belt 17 passing around the drive wheel 5 and the pulley 16 serving as a means for driving the shaft 14 and the cutter thereon. A guard rod 18 is attached to one of the bars 10 serving to hold the belt in place against any accidental removal from the pulley 16 while the opposite bar has a guard 19 of substantially the formation shown in Fig. 1 against which chips or the like thrown from the cutter 15 strike, stopping them from getting on to the car platform or the engine. This guard is attached to the side 10 by a suitable angle bracket indicated at 20.

The block 13 has passing therethrough an upright screw threaded shaft 21, the upper end of which carries a hand wheel 22 while its lower end bears upon a metal plate 23 attached to the member 6. Any suitable interiorly screw threaded nut is formed in the block 13 for the reception of the screw and it will be evident that by operating handle 22 the cutter 15 may be raised or lowered to any desired position between certain lim-

its. It will be further evident that the cutter 15 may be of any desired type and as it is removably attached to the shaft 14 may be replaced at any time by any other suitable appliance such for instance, as a grinding wheel or the like.

In the use of the mechanism for framing timbers a platform is provided as indicated at 24 on which short lengths of rails 25 are secured for carrying the hand car. A handle 26 is detachably attached to one of the wheels 2 by means of the hooks 27 engaging with two of the spokes of the wheel, these hooks being tightly engaged with the spokes on tightening the nuts 28 on the ends of the screws as shown in Fig. 2. By loosening the nuts the handle may be entirely removed from the hand car as when it is to be used to traverse a track. In front 20 of the platform 24 a truck 29 is positioned being mounted on rails 30 so as to move back and forth in front of the platform. A timber 31 is laid on the truck and brought to any desired position for framing. With the 25 cutter 15 in motion and driven by the engine it will be evident that as it is moved back and forth across the timber it will cut material therefrom and the depth of the cut may be regulated by operating the screw 30 21 while the width of the cut may be controlled by moving the truck 29 back and forth in front of the cutter 15. By 35 grasping the handle 26 the car with the attachment thereon is moved back and forth to carry the cutter across the timber and a straight cut such as indicated by the dotted outline 32 is made.

With this construction timbers may be 40 very rapidly framed without the use of skilled labor and the framing will be equal

to or better than that produced by most skilled laborers. The attachment may be readily removed from the car by merely withdrawing the pin 9 and removing the handle 26 whereupon the car may be used 45 to traverse a track in the usual manner and it can be quite as easily added when desired for the purpose of framing timbers. This attachment is of very simple construction but one of great utility as has been 50 found in actual practice over a period of several months. Slight changes in minor details of construction may be resorted to without departing from the invention which is defined in the appended claim. Accordingly 55 I do not wish to be limited to the exact construction shown but consider myself entitled to all modifications falling within the scope of the claim.

I claim:—

In combination with a car, a handle secured to a wheel of the car for moving the car a limited distance in either direction, a motor on the car, a member mounted on and projecting in front of the car, a shaft carried in the forward end of the member, a rotary cutter attached to the shaft, means to drive the shaft from the motor whereby said shaft and cutter thereon may operate simultaneously with the movement of the car, and a work holding truck located in front of said car and mounted to move in a direction transverse to the movement of the car, said cutter lying above the truck, and said truck adapted to carry the work 70 operated upon by the cutter, substantially as and for the purpose described.

In testimony whereof I affix my signature.

JOHN E. TOOHEY.
